UNITED STATES PATENT OFFICE.

SAMUEL H. GILSON, OF SALT LAKE CITY, UTAH, ASSIGNOR OF ONE-THIRD TO JAY S. MILNER, OF SALT LAKE CITY, UTAH.

AEROPLANE.

964,771.

Specification of Letters Patent. Patented July 19, 1910.

Application filed July 27, 1909. Serial No. 509,898.

To all whom it may concern:

Be it known that I, SAMUEL H. GILSON, a citizen of the United States, residing at Salt Lake City, in the county of Salt Lake and 5 State of Utah, have invented certain new and useful Improvements in Aeroplanes, of which the following is a specification.

The purpose of my invention is to provide an aeroplane that will automatically maintain its equilibrium, and to provide steering mechanism that will enable an aviator to direct the aeroplane to the right or left, and up or down without disturbing the equilibrium. These objects I attain by the device 10 illustrated in the accompanying drawings in which similar characters of reference indicate like parts throughout the several figures.

Figure 1 is a rear elevation showing the 20 equilibrium disturbed and aeroplane out of poise, with parts removed. Fig. 2 is a side elevation with the equilibrium reestablished. Fig. 3 is a plan view with an even keel. Fig. 4 is a front elevation in detail of modified form of part of balancing device. Fig. 25 5 is a plan view of the modified form of said parts. Fig. 6 is perspective showing all frames covered. Fig. 7, is an enlarged isometric view of a portion of the lower 30 frame, the truss and parts carried thereon. Fig. 8, is an enlarged vertical section on line *a a* of Fig. 7.

The frame of my aeroplane is made of horizontal tubes, 1 and 2, parallel to each 35 other and spaced apart by vertical tubes 3 and lateral tubes 4, and stayed by diagonal rods or wires 5. My balancing mechanism is equally applicable to mono-planes or multi-planes, and it is not my purpose to restrict 40 myself to the bi-plane shown, as slight modifications which will be readily apparent to anyone, may be made to adapt my balancing and guiding parts to mono-planes or multi-planes.

45 The plane formed by the horizontal tubes 1, and the lateral tubes 4, herein designated as plane 1', and the plane formed by the horizontal tubes 2 and the lateral tubes 4, herein called plane 2', are each covered with 50 silk or other suitable covering, tightly secured thereover, except the end spaces or squares of the lower plane marked A and A', each of the spaces having flat springs secured therein. One end of each of said

55 springs is firmly secured on the outer lateral tube 4, and to the other end of said springs 6 is attached the cross bar 7. The covering for these spaces A and A' is tightly drawn over the tubes 4 and cross bar 7 for the ends, and over the said spring 6 on the sides, 60 thus making smaller planes in each of said squares A and A', the greater portions of which may be raised above the horizontal bars 1, as shown in Fig. 1, by the cords 50 and 50'. The ends of the horizontal tubes 65 2 are bent downward, as the arc of a circle, and fastened to the ends of the horizontal tubes 1, and the cross bar 7 has openings in the ends thereof, and is adapted to slide on the bent portions of said horizontal tubes 2. 70 If desired the parts of the horizontal tubes 1 and 2 which extend beyond the outer vertical tubes 4 may be cut off.

Parallel with the horizontal tubes 1, and 75 extending over three of the lateral tubes 4, and carried by said tubes 4 are two or more truss supports 8; on said truss supports 8 are carried the anti-friction rollers 9. Carried by and riding on said rollers 9, is the shifting rack 10, to the ends of which rack 80 are secured the cords 50 and 50'. The said shifting rack 10 has teeth 11 cut on the upper side thereof, and on the under side has a longitudinal channel 51 adapted to receive the periphery of said rollers 9. The said 85 teeth 11 of said rack 10 mesh with the cogs 93 of a gear 12; the said gear 12, and a pinion 13, are carried by the shaft 14, which shaft 90 is mounted in the bearing frame 15, which bearing frame is carried on and by the said 95 truss supports 8.

In bearings suspended from the horizontal tubes 1, and under the truss supports 8, is mounted the rocking shaft 16. Carried by said rocking shaft 16, and rigidly secured thereon is the segment gear 17, the teeth or cogs of which mesh with said pinion 13. The depending arms 18 of said rocking shaft 16, are formed each with two 100 extremities to which is attached the boat 19. This boat 19 may be covered with material that will float in water, or it may be covered with any light material, more in the nature of a basket. Within the boat 19 the aviator, the motive power and the steering 105 mechanism for the aeroplane is carried.

From the horizontal tubes 1, to the upper side of the boat four spring stays 47 are

supplied, the greater portion of each of which is a spiral spring. The purpose being to provide a stay between said boat and frame 1', which will hang loosely except when the planes 1' and 2' are much deflected from the horizontal. In that case on one side the stays will be tightened, and on the other loosened, the intention being to so adjust the stays 47 that it will be impossible 10 for the edges of the boat to strike the planes. On one side of the plane 1', herein called the front side, is rigidly attached a semi-circular frame 20 and stay rods 21. Said frame 20 is placed at an obtuse angle 15 to the plane 1'. To two of the vertical tubes 3, and on the opposite side from the semi-circular frame 20, is pivoted the tail piece 36, which tail piece is braced by a truss support 8' similar to the truss supports 8. 20 A power driven shaft 22 is mounted in bearings on said boat 19, and, on each end of said shaft is secured a beveled friction gear 23. Said shaft 22 also carries the driven pulley 24.

25 Mounted in bearings 25, one on each side of the boat 19, are the propeller shafts 26, and provided on one end of each of said shafts 26 are the cone-shaped friction pinions 27. Said shafts 26 also carry on their 30 other ends the propeller blades 28, and have also fitted thereon clutches 29, which clutches enable the aviator to throw one or both propellers out of or into commission when and as desired. Within the front part 35 of said boat 19 is provided the steering means which consist of a horizontally placed drum 30, on which is secured the hand wheel 31, and on said drum 30 is wound the cord 32, one end of which cord passes over pulleys 33 and 34, which are secured near the bottom of the boat 19, and then over pulley 35 near the top of said boat 19, and is secured to the truss support 8' of the tail piece 36. The other end of said cord 32 is 40 passed over the pulleys 37, which are fastened to the horizontal bars 2, and the end is also secured to said truss support 8', opposite the point where the other end is secured. Also in the front of the boat 19 is secured a vertical drum 38, with a hand wheel 39 secured thereto. On said drum 38 is wound a portion of another cord 40, the 45 ends of which are passed over the pulleys 41, and are then secured to a rudder 42 that is pivoted at one end on the front of said boat 19. Said boat 19 may have bicycle wheels 43, fitted on the under side thereof, for use in starting, and carried by the axle of the rear bicycle wheels is the power 50 driven pulley 44, which is run by the belt 45, when desired.

55 A modified form of my automatic balancing device is shown in Figs. 4 and 5, and consists of a drum 46, that is secured on said shaft 14 in place of the gear 12, and in the

modified form, the shifting rack 10 is not used, as the cords 50 and 50' are wound on the said drum 46, as shown in Fig. 5. The rotation of the drum, which is effected by the same segment gear 17 and pinion 13, 70 will flex the springs 6 in this form, the same as the shifting of the rack 10 in the other form.

75 Any form of motive power may be used. A belt from one side of said power incloses pulley 24, the said belt 45 being connected with the other side of said power.

Motion being imparted through the belt 45 to my device, it will move rapidly on the ground. When sufficient motion is secured the propellers 28 may be thrown into commission by the clutches 29, which enables the aviator to gradually introduce the power through the friction gears. After 80 the aeroplane has raised sufficiently in the air for the wheels 43 to be clear of the ground, any deviation from the horizontal by the planes 1' and 2', will be corrected by the boat 19 acting as a pendulum, and by means of the segment gear 17, the pinion 90 13 and the shifting rack 10 (or the drum 46, as shown in the modified form if that is used.) The movement in either form will flex the springs 6, and turn up the edge of the space A or A', depending upon which 95 side of the aeroplane is the lower. The other space will not be affected by said motion and will remain in line with plane 1'. This will cause the planes 1' and 2' to right themselves and assume the horizontal of two 100 equilibriums.

Having thus described my invention I desire to secure by Letters Patent and claim;

1. An aeroplane comprising a covered frame, end planes secured thereto, a supporting truss carried by said frame, rollers mounted on said truss, a shifting rack having a longitudinal channel on its lower side and teeth on its upper side, a cord which reaches from each end of said rack to the outer end of the end plane adjacent a bearing frame also secured on said truss, a shaft mounted on said bearing frame, a gear and a pinion on said shaft, the teeth of which gear are adapted to mesh with the teeth 110 of said shifting rack, a rocking shaft secured on said frame and transversely thereto, a segment gear and depending arms secured on said rocking shaft, the teeth of said segment gear adapted to engage with the pinion, a boat secured to the depending arms of said rocking shaft, and propelling means carried in said boat. 115

2. An aeroplane comprising a covered frame, a resilient plane attached on each end thereof, a supporting truss carried by said frame, rollers mounted on said truss, a shifting rack having a longitudinal channel on its under side and teeth on its upper side, a cord which reaches from each end 120 130

of said rack to the outer end of the resilient plane adjacent, a bearing frame also secured on said truss, a shaft mounted in said bearing frame, a gear and a pinion on said shaft, the teeth of the gear adapted to mesh with the teeth of said shifting rack, a rocking shaft secured to said frame transversely thereto, a segment gear and depending arms secured on said rocking shaft, the teeth of said segment gear adapted to engage the said pinion, and a boat secured to the depending arms of said rocking shaft.

3. An aeroplane comprising a covered frame, a covered plane secured to each end thereof a portion of which may be bent, a frame secured on one side of said first named covered frame at an angle thereto, a movable tailpiece pivoted to the other side of said frame, means for moving said tailpiece up and down, a supporting truss carried by said first mentioned frame, rollers mounted on said truss, a shifting rack having a longitudinal channel in its under side and teeth on its upper side, a cord connected at each end thereof and to the outer end of the plane adjacent, a bearing frame, a shaft mounted therein, a gear and a pinion on said shaft, the teeth of the gear adapted to mesh with the teeth of said shifting rack, a rocking shaft secured to said covered frame transversely thereto, an upper arm on said rocking shaft formed as a segment gear the teeth of which are adapted to engage with the pinion, depending arms on said rocking shaft and propelling means for the device carried by said arms.

4. An aeroplane comprising two covered frames parallel and spaced apart, covered resilient members attached to the outer ends of one of said frames and which normally lie in the same horizontal plane, and means secured to one of said frames to automatically bend said resilient members, which means consists of a boat pivotally secured to the lower one of said frames, and adapted to hang normally at right angles to said covered frames, and means carried on said boat adapted to automatically co-act with the members connected therewith on one of said frames, whenever the said boat assumes a

position other than at right angles to the covered frames.

5. An aeroplane comprising a covered frame, and planes attached thereto which may be warped, a boat pivotally secured to said covered frame normally at right angles thereto, means secured to the boat to warp said end planes whenever the said covered frames assume a position other than at a right angle to said boat, a power driven shaft mounted in said boat, beveled friction gears one on each end of said shaft, propeller shafts mounted in bearings on the side of said boat, a beveled pinion on one end and propeller blades on the other end of each of said propeller shafts, said pinions being adapted to engage said first named bevel pinions, and clutches on said shafts adapted to move said shafts longitudinally.

6. An aeroplane comprising a covered frame, a covered plane secured on each end thereof with resilient members therein, a supporting truss carried by said frame, rollers mounted on said truss, a shifting rack having a longitudinal channel on its lower side and teeth on its upper side, cords connected at each end of the rack to the outer ends of the said covered planes, a bearing frame also secured on said truss, a shaft mounted in said bearing frame, a gear and a pinion on said shaft, the teeth of the gear adapted to mesh with the teeth of said shifting rack, a rocking shaft secured to said covered frame transversely thereto, a segment gear secured on the upper part of said rocking shaft, the teeth of said segment gear adapted to engage the said pinion, depending arms on said rocking shaft, a boat secured to the said arms, spring stays secured to the upper side of said boat and to the lower side of said covered frame, a movable tailpiece pivoted to said frame and means for adjusting said tailpiece.

In testimony whereof I have affixed my signature in presence of two witnesses.
